CATALYTIC HEATER HEAD ATTACHMENT

George G. Vidmar, Jr., Independence, Kans., assignor to
Bruest Industries, Inc., Independence, Kans.

Filed May 21, 1973, Ser. No. 361,983

Term of patent 14 years

Int. Cl. D23—03

U.S. Cl. D23—137

Fig. 1.

Fig. 2

Fig. 3.

Fig. 4.

FIG. 1 is a top, front, perspective view of the catalytic heater head attachment, showing my new design from one side thereof;

FIG. 2 is a front elevational view thereof;

FIG. 3 is a top plan view of the attachment; and

FIG. 4 is an elevational view of the side opposite that shown in FIG. 1.

I claim:

The ornamental design for a catalytic heater head attachment, as shown.
